ENAMELED ARTICLE

Joseph T. Penton, Los Angeles, Calif.

Application February 17, 1936, Serial No. 64,273

14 Claims. (CL 189—34)

This invention relates to vitreous enameled articles such as signs, panels, fittings, fixtures, utensils, etc. A general object of this invention is to provide enameled articles embodying simple, 5 practical and particularly effective means for attaching them to other parts or for connecting handles, knobs, frames or similar members to them.

Much difficulty is usually encountered in attaching vitreous enameled articles to their supports and in securing handles, frames, etc., to vitreous enameled articles. It has been the usual practice to provide openings in the enameled parts for the reception of screws, bolts or other 10 securing members for attaching the articles to their supports, for holding the articles assembled or for securing handles, frames and the like to the enameled articles. It is necessary to form or provide the openings in the metal base 15 of an enameled article before applying and firing the vitreous enamel, because the openings cannot be formed in the finished vitreous enameled article without cracking and breaking loose the enamel. When the screws, bolts or other securing members passing through the openings in 20 an enameled article are tightened down against the vitreous enamel or against washers or grommets engaging the enamel, the enamel adjacent the openings is often chipped and broken loose. 25 Further, as the openings must be provided in the metal base of an enameled article before the application and firing of the enamel it is essential that the openings be very accurately located because they cannot be enlarged without injuring 30 the enamel and the article cannot be bent or strained to align the openings without cracking and injuring the enamel.

Another object of this invention is to provide a vitreous enameled article having a connecting 40 or attaching means whereby it may be firmly connected to a support or the like or may have a part rigidly secured to it without danger of cracking, chipping or otherwise injuring its enamel.

45 Another object of this invention is to provide a vitreous enameled article having means whereby it may be easily and conveniently secured in its proper place with relation to other members without requiring the provision of accurately located openings before it is enameled.

50 Another object of this invention is to provide a vitreous enameled member or article having an attaching part or parts that may be in the form of a handle, frame, decoration, trimming, or 55 the like, that may be polished, painted or other-

wise finished as desired. The invention contemplates the provision of one or more attaching parts on an enameled article that may serve solely as a means for facilitating the mounting of the article or the connection of other parts to the article without injuring its enamel and that may be shaped, formed and located to also serve as a handle, frame, decoration, trimming or the like capable of being finished as may be required.

5 Another object of this invention is to provide 10 an enameled article having one or more attaching parts welded to its base that may be provided with openings either before or after embodiment in the article and that may be bent or shaped as required to serve as a means for attaching the 15 enameled article to a support or as a means for securing a handle, frame or other element to the article without injuring or endangering the enamel.

Another object of this invention is to provide 20 an enameled article of the character mentioned in which the attaching part or parts are welded to its base before applying and firing the enamel and that do not in any way interfere with the 25 enameling process.

Another object of this invention is to provide 30 an enameled article of the character mentioned in which the attaching part or parts are rust-proof, capable of resisting high temperature, easily welded, capable of being polished and painted and that are malleable so that they may 35 be shaped or formed as desired thereby greatly facilitating the attaching or mounting of the enameled article.

The various objects and features of my invention will be fully understood from the following 40 detailed description of typical preferred forms and applications of my invention, throughout which description reference is made to the accompanying drawing, in which:

45 Fig. 1 is an elevation view of one form of the invention. Fig. 2 is an enlarged fragmentary detailed sectional view taken as indicated by line 2—2 on Fig. 1. Fig. 3 is an elevation view of another form of the invention. Fig. 4 is an enlarged fragmentary detailed sectional view taken substantially as indicated by line 4—4 on Fig. 3. Fig. 5 is a view similar to Fig. 4 showing the 50 projecting portion of the attaching part bent at substantially right angles to the base of the article. Fig. 6 is an elevation view of still another form of the invention. Fig. 7 is an enlarged fragmentary detailed sectional view taken substantially as indicated by line 7—7 on Fig. 6 and Fig. 8 is a view similar to Fig. 7 illustrating 55

a typical manner of employing the attaching part.

The present invention is adapted to be applied to or embodied in vitreous enameled objects and articles of various characters and may be employed for various purposes depending upon the character of the enameled article. In the following detailed disclosure several typical forms of the invention will be disclosed as applied to or embodied in simple panel-like or plate-like enameled articles, it being understood that the invention may be embodied in or applied to articles of various shapes and in some instances may be modified to some extent because of the shape or character of the articles.

The application or form of the present invention illustrated in Figs. 1 and 2 of the drawing comprises, generally, a body or base 10 having a coating or covering of enamel 11 and one or 20 more attaching parts 12 on the base 10.

The base 10 of the article shown in Figs. 1 and 2 of the drawing may be of any size and shape, the size and shape of the base 10 depending, of course, upon the character of the device or article. In the drawing, which is merely illustrative of the invention, the base 10 is a simple, rectangular plate-like part. The base 10 is formed of iron, it being preferred to form the base 10 of what is known as enameling iron that is 25 readily adhered to by the vitreous enamel. The enamel 11 preferably covers all the surfaces of the base 10 except those surfaces covered by the attaching parts 12. The enamel coating 11 which is vitreous enamel is applied by means of 30 the well known process which includes the placing of the base 10 in a pickle bath, the applying of a ground coat or bond coat of porcelain enamel to all the exposed surfaces of the base 10, the firing or vitrifying of the base coat, the application 35 of colored enamel or designs of colored enamel to one or more surfaces, and the firing or vitrifying of these colored or design coats of enamel.

In accordance with the form of the invention 45 being described the base 10 is provided with one or more openings 13. The number of openings 13 provided in the base 10 depends upon the number of attaching parts 12 to be applied to or used on the article. In the typical case shown in the drawing there are four transverse openings 13 in the base 10, there being one opening 13 in each corner portion of the base. The openings 13 are drilled or punched in the base 10 before the enameling process described above. The 50 openings 13 are preferably larger in diameter than the heads of the screws or securing members intended to be used in attaching or mounting the article. As the openings 13 are provided in the base 10 prior to the enameling process the enamel 11 coats or covers their walls as clearly shown in Fig. 2 of the drawing.

The parts 12 are provided on the article to facilitate its attachment to a support or the like or to facilitate the connecting of members to the article. In accordance with the broader aspects of the invention the attaching parts 12 may be provided on either one or both of the principal surfaces of the base 10. In the simple application of the invention shown in the drawing the parts 12 are provided on what I will term the rear surface or side 14 of the base 10. The attaching parts 12 are simple plate-like members and may be of square or rectangular outline or of any other desired configuration. The parts 70 75 12 are formed of metal and are welded to the

base 10 as at 15. It is preferred to form the parts 12 of stainless steel or an alloy that is rust resistant, capable of withstanding high temperatures, that is low-scaling, easy to weld and punch and that is malleable so that it may be bent or shaped 5 either before or after the enameling process.

The attaching parts 12 are welded to the rear side 14 of the base 10 so that they extend across or cover the rear ends of the openings 13. When the ground or base coat of enamel is applied to 10 the base 10 it covers or coats the parts 12. During or subsequent to the enameling process the enamel on the parts 12 may be easily and quickly removed by jarring or striking the parts. As the enamel does not readily adhere to the metal of 15 the parts 12 and very effectively adheres to the enameling iron of the base 10 the enamel may be easily removed from the parts 12 as just described without injuring or endangering the enamel on the base 10. Accordingly, the enamel 20 on the parts 12 may be easily removed after the enameling process to leave the surfaces of the parts 12 clean and exposed for bearing on supports or the like and for engagement by screws or securing members.

In accordance with the invention the parts 12 may be provided with openings 16 to pass or receive securing parts such as screws, bolts or the like. Each part 12 may be provided with an opening 16 to register or communicate with an 30 opening 13 in the base 10. The openings 16 may be punched or drilled in the parts 12 either before or after the welding of the parts to the base 10 or before or after the enameling of the base. In instances where the openings 16 must accurately 35 align with openings in the support or member to which the article is to be attached it may be found desirable to drill the openings 16 in the parts 12 after the enameling process and when the article is ready to be mounted or attached 40 to its support. The openings 16 are preferably somewhat smaller than the openings 13 so that the heads of the securing members may be received in the openings 13 with clearance and may engage the parts 12 at the bottoms of the openings 13. In the drawing I have shown typical screws 17 arranged through the openings 16 to attach the enameled article to a support or the like. The heads of the screws 17 are received in the openings 13 with clearance, that is, they do not engage or contact the enamel 11 coating the 45 walls of the openings. The heads of the screws 17 are adapted to directly bear on or engage the parts 12 so that tightening down of the screws 50 may be accomplished without cracking or otherwise injuring the enamel 11. The screws 17 or other securing members may be such that their heads are entirely received or countersunk in the openings 13. Thus the screws 17 or members securing the enameled article to its support need 55 not protrude from the outer surface of the article. It is believed that it will be apparent how the enameled article may be easily and quickly attached to a support or the like by the screws 17 or similar connecting members without endangering the enamel 11.

The form or application of the invention disclosed in Figs. 3, 4 and 5 of the drawing includes, generally, a base 20 having an enamel covering or coating 21, and attaching parts 22 on the 70 base 20.

The base 20 may be of any size and configuration, the size and configuration of the base depending, of course, upon the character of the enameled article. In the simple application of 75

the invention shown in the drawing, the base 20 is a rectangular plate-like part. The base 20 is preferably formed of enameling iron and is covered or coated with vitreous enamel 21. The 5 vitreous enamel 21 may be applied to the base 20 in the well known manner described above in connection with the previously described form of the invention. So far as the form of the invention being described is concerned, the base 20 10 may be an imperforate part as the attaching means does not necessitate the provision of openings in the base. The enamel 21 may cover all the surfaces of the base 20 with the exception of those surfaces covered by the attaching parts 15 22.

The securing or attaching parts 22 are provided along one or more edges of the base 20. In the typical case illustrated in the drawing the attaching parts 22 extend along two opposite 20 edges of the base 20. The attaching parts 22 are elongate strips and there may be a single part 22 extending throughout the length of each edge 23 of the base. The parts 22 may be attached to either one or both of the principal surfaces of the base 20. As shown in the drawing the parts 22 are provided on what may be termed the rear side or surface of the base 20. In accordance with the invention the parts 22 are welded to the base 20 as at 24. The parts 22 30 project outwardly beyond the edges 23. The portions of the parts 22 projecting beyond the edges 23 form means for facilitating the attachment or connection of the enameled article with supports or other parts. Accordingly, the projecting portions of the parts 22 may be provided with openings 25 for passing or receiving securing members such as screw bolts or the like. In the drawing I have shown longitudinally spaced openings 25 provided in the projecting portions of the parts 22. The openings 25 may be formed in the parts 22 before the parts are welded to the base 20 or may be drilled in the parts 22 after the enameling of the base 20.

The attaching parts 22 are formed of a metal 45 that is easily welded, capable of resisting high temperatures, low scaling, non-rusting, and that is flexible and readily polished. If desired or found necessary, the projecting portions of the attaching parts 22 may be bent or disposed at an angle to the base 20 as illustrated in Fig. 5 of the drawing. The parts 22 may be bent or shaped as illustrated in Fig. 5 either before the parts are welded to the base 20 or after the enameling of the base. The parts 22 may be 50 readily shaped to engage supports or the like and thus facilitate the securing or mounting of the enameled article. It is to be understood that the attaching parts 22 may be polished or finished as desired. When the parts 22 are employed to 55 connect the enameled article with adjacent enameled articles or panels in the same or parallel planes they may project outwardly as illustrated in Fig. 4 of the drawing to form spacers or bands at the opposite ends of the article and may be polished or finished in any other manner. The attaching parts 22 may be coated with the ground 60 coat of enamel during the enameling process and this coat of enamel may be easily removed or broken free from the parts 22, during or following the enameling process, by wiping, striking or bending them without endangering the enamel on the base 10 as the enamel very effectively adheres to the enameling iron of the base.

In addition to the attaching parts 22 the article 75 shown in Figs. 3, 4 and 5 of the drawing may be

provided with attaching parts in the form of tabs or lugs 26. The lugs 26 are welded to a surface or side of the base 20 to project beyond a selected or desired edge or edges of the base. In the simple form of the invention illustrated in the drawing the lugs 26 are welded to the rear side of the base 20 to project beyond its upper and lower edges. In accordance with the invention the lugs 26 are spot welded to the base 20 before the base is enameled. The lugs 26 are preferably formed 10 of the same metal as the parts 22. The enamel may cover the surfaces of the lugs 26 and may be easily broken free from the lugs 26 when desired without injuring the enamel on the base 20. As the lugs 26 are malleable or flexible they 15 may be bent or shaped to project from the base 20 at right angles or at any other angle to facilitate the connection of the base with supports or the like. Each lug 26 may be provided with one or more openings 27 to receive securing members 20 such as bolts, screws or the like. The openings 27 may be provided in the lugs 26 before the welding of the lugs to the base 20 or following the enameling of the article. It is believed that it will be readily understood how the attaching 25 parts 22 and the lugs 26 may be employed to conveniently attach or connect the enameled article with supports or adjacent members without cracking or otherwise injuring the vitreous enamel on the base. 30

Figs. 6, 7 and 8 of the drawing illustrate a form of the invention that is particularly easy and convenient to handle and which have a connecting or attaching means that does not project beyond the edges of the article. The enameled 35 article illustrated in Figs. 6, 7 and 8 of the drawing includes, generally, an enameled base 30 and securing or attaching parts 31 on the base.

The base 30 may be a simple, plate-like rectangular part as shown in the drawing or may 40 be of any other shape, depending upon the character of the article. The base 30 is formed of enameling iron so that the vitreous enamel effectively adheres to it. A coating or covering of vitreous enamel 32 is provided on the base 30. 45 The enamel 32 preferably covers all the surfaces of the base 30 except those portions of its surface covered by the parts 31. The enamel 32 may be applied to the base 30 in the manner described above. 50

The attaching parts 31 are provided on what may be termed the rear side 33 of the base 30. The parts 31 are elongate members or strips of flexible non-rusting, low-sealing, high temperature resistant metal that is easy to weld and 55 capable of being polished. There may be as many attaching parts 31 as desired and the parts may be located as required to facilitate the connection or attachment of the article to supports or other members. In the instance illustrated in the 60 drawing there are two parts 31 in spaced parallel relation on the upper portion of the rear side 33 and a third part 31 located substantially in the middle or center portion of the rear side 33. In accordance with the invention each attaching 65 part 31 has one end portion welded to the base 30. The parts 31 are preferably spot welded to the base 30 as at 34. The parts 31 are welded to the base 30 before the enameling of the base. 70

In accordance with this form of the invention 75 the attaching parts 31 lie flat or substantially flat against the rear surface 33 of the base 30. The parts 31 are preferably, though not necessarily, proportioned and located so that they do not project beyond the edges of the body. When 75

proportioned and located in this manner the parts 31 may be easily handled, packaged and shipped. The base coat or cover coats of enamel may cover the exposed surfaces of the parts 31 and may be easily broken loose from the parts 31 during or following the enameling process by brushing, striking or bending the parts. The outer or free portions of the parts 31 may be bent away from the base 30 when it is desired to 10 employ the parts to attach or connect the base 30 with supports or other members. The parts 31 may be sufficiently long so that they may be readily bent or shaped to engage supports or other members of various shapes and to assist in 15 connecting the base 30 with the supports. For example, as shown in Fig. 8 of the drawing a part 31 may be bent outwardly at right angles to the base 30 and may then be bent to have a part parallel with the base 30 and a part projecting 20 inwardly toward the base so as to fit about a support or member M. It is obvious, of course, that the attaching parts 31 may be formed in various other manners to engage or connect with supports or members of other shapes, etc. If desired or found necessary the parts 31 may be provided with one or more openings to receive bolts, screws or other securing members. These 25 openings may be provided in the parts 31 either before the parts are welded to the base 30 or following the enameling of the base.

Figs. 6, 7 and 8 of the drawing illustrate a form of the invention in which the attaching means does not provide parts projecting from the edges of the enameled article to interfere with the packaging or shipping of the article. The attaching parts 31 may be located and proportioned to constitute simple effective means for dependably attaching or connecting the enameled article with supports or the like.

40 It is believed that the utility and practicability of the articles of the present invention will be readily apparent from the foregoing detailed description. The invention provides various forms of simple effective means for dependably attaching or connecting an enameled article with a support or other part without endangering the vitreous enamel of the article. The attaching parts welded on the base of the enameled article may be engaged, manipulated and tightened down by 45 securing members such as screws, bolts or the like without cracking or otherwise injuring the enamel of the article. Further, the welded or attaching members may be provided with openings of various sizes and located so as to properly register with other openings in the supports or the like to facilitate the reception of the bolts or securing members without straining or bending the enameled article. This is very important in securing enameled articles and panels to their supports, etc. The provision of the attaching parts does not complicate the enameling process and the parts may be very simply and inexpensively provided on the articles. If desired, the welded-on attaching parts may comprise borders or decorations on the edges or surfaces of the enameled article somewhat as shown in Fig. 3 of the drawing and may be polished or otherwise finished to provide a contrast with the vitreous enamel of the article. The present invention completely 55 overcomes the difficulties heretofore encountered in attaching and connecting vitreous enameled articles with their supports or other members.

70 It is believed that the manner of making the articles of the present invention will be understood from the foregoing detailed description of

the several typical articles of the invention and their mode of manufacture. Referring to Figs. 3, 4 and 5, for the purpose of example, the method of procedure may be said to comprise, generally, providing two parts 20 and 22, assembling 5 or connecting the parts, placing the assembly 20 and 22 in a pickle bath, applying a bond or ground coat to the surfaces of the assembly 20 and 22, applying other coats of porcelain enamel to the assembly 20 and 22 as required, successively firing or vitrifying the several enamel coats, removing the enamel from one of the said parts by flexure, or the like either during or after the enameling process and then employing the said part as a means for securing or attaching 10 the other part to a support or other element. The various steps of the process just outlined have been set forth in detail in the foregoing description. It is to be noted, however, that the step of assembling or connecting the parts of the 20 article by welding permits the flexure of the attaching part relative to the base to readily break the enamel joint between the parts and to remove the vitreous enamel from the fastening or attaching part without endangering or injuring 15 the enamel on the other part or base during or following the enameling process. The steps of pickling the assembly, applying the enamel coats and the firing of the vitreous enamel in carrying out the enameling process are not in any way 20 complicated by the presence of the attaching or fastening part or parts of the article. The attaching part or parts being flexible and malleable form a convenient means for attaching or securing the vitreous enameled base to another element or assembly.

Having described only typical preferred forms and applications of my invention I do not wish to be limited or restricted to the specific details herein set forth, but wish to reserve to myself any 40 variations or modifications that may appear to those skilled in the art or fall within the scope of the following claims:

Having described my invention, I claim:

1. An article of manufacture comprising a metallic base, a connecting part connected directly with the base to facilitate the connection of the base with an object, and a vitreous enamel covering on the base, the said part having a low adherence to enamel and being flexible whereby 45 enamel adhering to it may be readily broken therefrom to leave the surface of the part clean.

2. An article of manufacture including a metallic base having a coating of vitrified enamel, and a part of metal to which vitreous enamel will 55 not readily adhere attached directly to the base and projecting beyond an edge thereof to facilitate the connection of the base with an object.

3. An article of manufacture including a metallic base having a coating of vitrified enamel, and a part of metal to which vitreous enamel will 60 not readily adhere attached directly to the base and projecting beyond an edge thereof to facilitate the connection of the base with an object, the projecting portion of the said part having an opening for receiving a securing member.

4. An article of manufacture including a metallic base having a coating of vitrified enamel, and a part of metal to which vitreous enamel will not 70 readily adhere attached directly to the base and extending longitudinally along one edge of the base and projecting outwardly beyond said edge to facilitate the connection of the article with an object.

5. An article of manufacture including a metal-

- lic base having a coating of vitrified enamel, and a part of metal to which vitreous enamel will not readily adhere attached directly to the base and extending longitudinally along one edge of the base and projecting outwardly beyond said edge to facilitate the connection of the article with an object, there being longitudinally spaced openings in the projecting portion of the said part to receive securing parts.
- 5 6. An article of manufacture comprising a metallic base having an opening, a coating of vitrified enamel on the base, and a part permanently and directly attached to the base and extending across the opening to facilitate the attachment 10 of the article to an object, said part being formed of metal having a low adherence to vitreous enamel.
- 15 7. An article of manufacture comprising a metallic base having an opening, a coating of vitrified enamel on the base, and a part integrally joined directly to the base and extending across the opening, the part having an opening to receive a securing member, and being formed of metal to which vitreous enamel will not readily adhere.
- 20 8. An article of manufacture comprising a metallic base having an opening, a coating of vitrified enamel on the base, and a part of metal having a low adherence to vitreous enamel welded to a surface of the base to cover one end of the opening, the part having an opening registering with the first mentioned opening and adapted to receive a securing member, said part being free of enamel at the margin of its opening.
- 25 9. An article of manufacture comprising a metallic base, a coating of vitrified enamel on the base, and a flexible securing part of metal having a low adherence to vitreous enamel attached di- 30 rectly to a surface of the base and adapted to be flexed outwardly therefrom to form an attaching tab.
10. An article of manufacture comprising a metallic base, a coating of vitrified enamel on the base, and a flexible securing part of metal having a low adherence to vitreous enamel having one end portion secured directly to a surface of the base so that its opposite end portion may be flexed outward to form an attaching tab.
11. A vitreous enameled article comprising a metallic base covered with enamel, and a flexible part of metal having a low adherence to vitreous enamel integrally connected with the base and projecting therefrom to facilitate the connection of the article with an object, the projecting portion of the part being angularly disposed relative to the base.
12. As an article of manufacture, a vitreous enameled metallic base, and a part of rust resistant metal to which vitreous enamel will not readily adhere, welded directly to the base to facilitate the connection of the base with an object.
- 20 13. A vitreous enameled article comprising a metallic base covered with enamel, and a flexible metallic part to which vitreous enamel will not readily adhere, integrally connected directly with the base and projecting therefrom to facilitate the connection of the article with an object.
- 25 14. A vitreous enameled article comprising a metallic base covered with enamel, and a part of rust resistant metal to which vitreous enamel will not readily adhere, connected directly to the base and projecting therefrom to facilitate the connection of the article with an object.
- 30 35

JOSEPH T. PENTON.
